UNITED STATES PATENT OFFICE

2,045,020

DUPLICATING MACHINE

Alfred Marchev, La Grange, Ill., assignor to Ditto, Incorporated, Chicago, Ill., a corporation of West Virginia

Application March 9, 1935, Serial No. 10,162

18 Claims. (Cl. 101—132)

This invention relates to duplicating machines and is particularly adapted to be embodied in a duplicating machine of the type wherein master sheets of paper are employed and the copy sheets are moistened with a suitable solvent for the ink or carbon on the master sheet, each copy sheet being brought in turn into contact with the master sheet so that the data on the master sheet will be duplicated on the copy sheet.

10 The master sheets are generally made by placing a piece of carbon paper against the back surface of a sheet of paper, and then the data to be duplicated is typed or written on the front surface of the master sheet so that it appears in reverse upon the back surface of the master sheet. Of course, it is not necessary to have the data appear on the front surface of the master sheet, and, therefore, it is not necessary to employ a ribbon in the typewriter during the typing operation.

20 In practice volatile solvents such as alcohol are employed. The solvents may be applied to the copy sheets in any suitable manner such for instance by a wick through which the solvents travel from a reservoir.

One form of the invention is embodied in a machine of the type described which comprises a frame having a duplicating drum mounted for rotation therein, said drum having means thereon for clamping the master sheet thereto. The copy sheets are advanced manually to the duplicating drum, and a platen roller is adapted to press the copy sheets against the master sheets during the duplicating operation. Means is provided for bringing the duplicating drum to a positive stop at the end of each cycle of operation.

As an example of the general type of machine referred to, such a machine is shown in the application of Morrison and Stewart, Serial No. 753,336, on Duplicating machines, filed November 16, 1934.

In machines of this character, the application of a new master sheet to the drum to replace an old one should be done quickly, and with as little possibility of inaccuracy in positioning as possible. A feature of this machine is the provision of means for quickly, applying and accurately positioning a new master sheet on the drum. Such means comprises a master sheet table, which

sheet clamping means and release the old master sheet, then to bring the open clamping means into alignment with the edge of the master sheet table and come to a positive stop with the clamp open at the front edge of the table. The closing 5 of the clamping means on the new master sheet is thereafter automatically accomplished by actuation of the drum rotating crank, and this operation also resets the manually operable mechanism for releasing the used master sheet and 10 for stopping the drum in position to receive a new master sheet.

Other features and advantages of the invention will become apparent as the following detailed description progresses, reference being had to the 15 accompanying drawings wherein—

Fig. 1 is a vertical sectional view through the machine;

Fig. 2 is a plan view of the machine;

Fig. 3 is a vertical sectional view on the line 20 3—3 of Fig. 2;

Fig. 4 is a vertical section on the line 4—4 of Fig. 3;

Fig. 5 is a fragmentary view partly in section showing on the line 5—5 of Fig. 7 a part of the 25 master sheet clamp closing means;

Figs. 6, 7, and 8 are fragmentary views showing different positions of the mechanism shown in Fig. 5;

Fig. 9 is a fragmentary section taken substantially on the same line as Fig. 4 showing a changed position of the mechanism;

Fig. 10 is a section like Fig. 9 showing another position of the mechanism;

Fig. 11 is a fragmentary view of the master 35 sheet clamping mechanism on the drum;

Fig. 12 is a fragmentary view like Fig. 11 showing a changed position of the clamping mechanism;

Fig. 13 is a fragmentary sectional view on the 40 line 13—13 of Fig. 11;

Fig. 14 is a fragmentary sectional view similar to Fig. 10 showing a further position of the master sheet replacing mechanism;

Figs. 15 and 16 are fragmentary sectional views 45 like Fig. 14 showing further positions of the master sheet replacing mechanism;

Fig. 17 is a fragmentary sectional view on the line 17—17 of Fig. 14; and

Fig. 18 is a fragmentary perspective of a portion of the master sheet table.

Referring to the drawings wherein a preferred embodiment of the invention is disclosed, the reference characters 20 and 21 designate two side frames adapted to rest upon any suitable support, 55

the side frames being provided with rubber feet 23 which rest upon the support. Interposed between the side frames 20 and 21 and rigidly secured thereto are braces 24 and 25.

5 Projecting through the frames 20 and 21 are bolts 26 and 27 which bolts carry a shaft 30. Rotatably journaled on the shaft 30 is a duplicating cylinder 32 provided with hubs 33 and 34. Bearings 28 and 29 are interposed between the shaft 30 and the hubs 33 and 34. It will be noted that packing 35 is provided in the hubs 33 and 34 to prevent loss of lubricant from the bearings.

10 The drum 32 is fabricated from a cylinder wall 37 and disks 38 and 39, the hubs 33 and 34 being preferably formed integral with the disks 38 and 39.

15 Referring to Fig. 3, it will be noted that the bolt 27 projects through the frame 20 and through a spacing collar 40 disposed adjacent the inner surface of the frame 20. The end of the shaft 30 terminates flush with the inner surface of the collar 40. It will also be noted from Fig. 3 that the bolt 26 extends through a sleeve 42 which has one end disposed within the frame 21. The end of the shaft 30 abuts against the end of the sleeve 42, and the inner end of the sleeve 42 is provided with an outwardly extending annular flange 43.

20 Disposed around the sleeve 42 and held between the flange 43 and a collar 44 is a bushing 46 on which a sleeve 48 is rotatably journaled. A gear 48 formed integral with the sleeve 46 meshes with a pinion 49 mounted upon a shaft 50 which is rotatably journaled in the frame 21. The inner end of the sleeve 46 is provided with an integral flange 52, and projecting from the inner surface of the flange 52 are diametrically opposed lugs 54. As shown more clearly in the prior application hereinbefore mentioned, the lugs 54 project into slots 55 in a hub 58 of a lever 59. The hub 58 is pivotally mounted on one end of the adjacent hub 33. The free end of the lever 59 is slotted at 60, and the slot 60 accommodates a bolt 61 which is fixed in a boss 63 on the disk 38 (Figs. 1 and 3).

25 It will be readily understood that the sleeve 48 can drive the lever 59 through the medium of the lugs 54, and that the lever 59 will in turn rotate the drum 32 through the medium of the bolt 61.

30 It will also be readily understood that the drum 32 can be angularly adjusted with respect to the lever 59. This adjustment may be made by loosening the bolt 61, moving the drum relative to the lever, and then tightening the bolt.

35 A crank arm 64 is connected by a shaft 65 which is rotatable within the shaft 50 to a cam member 66 which is in turn connected through a spring 67, a pin 68, and a boss 69 to the pinion 49 in the manner shown in the aforementioned application for the purpose of permitting rotation 40 of the crank arm 64, and the member 66 through a certain angle before the pin 68 will drive the pinion 49.

45 The member 66, as shown in Figs. 1 and 3, is adapted to engage a roller 67a on an arm 68a of a bell crank lever 69a to force a dog 70 out of engagement with a shoulder or tooth 71a formed on a disk 11 which is riveted to the flange 52, and thus release the drum so that it may rotate with further rotation of the crank 64.

50 The mechanism actuated by the member 66 and the bell crank 69a is of no further interest to the present invention and, therefore, will not be further described. However, this mechanism actuates a moistening device 72, a liquid feeding device 73, and a platen roller 74 in timed relation

55 to the rotation of the drum as described in the application hereinbefore mentioned. The copy sheets are carried upon a table 76a and are delivered onto a delivery table 78 in the usual manner, after the duplicating operation.

The new master sheets are carried upon a master sheet table 76. As illustrated best in Fig. 18, this table has thereon at the side thereof next to the frame member 20, an upstanding bracket 78. Below the bracket 78, a bracket 101 has one end riveted to a side flange 76a of the table 76, and pin 101a extends between the free end of the bracket 101 and the side flange 76a. At the front edge of table 76, a stop projection 103 is provided. The table 76 inherently functions as a 15 guide means to properly align the forward edge of the new master sheet. As illustrated best in Figures 2, 14 and 15 the front edge of the table 76 fits close to the drum surface and the table surface directs a master sheet thereon right into the 20 open clamping means when the drum is positioned to align the clamping means with the front edge of the table.

The mechanism cooperating with the table 76 including the clamping mechanism on the drum 25 for the master sheets will now be described in detail.

25 As shown most clearly in Figs. 1 and 4, the master sheet table 76 is pivoted to the frame members 20 and 21 by means of a rod 77. An arm 79 is pivoted to the upstanding bracket 78. This arm 79 has a cam surface 80 adapted to cooperate with a pin 81 (see Fig. 17) on the drum for swinging the arm 79 outwardly with respect to the drum as will be hereinafter more fully explained. A 35 shoulder 84 is formed on arm 79 at the top of cam surface 80. The arm 79 is pulled toward the drum by means of a spring 82 secured to a pin 83 on the frame 20. The arm 79 extends downwardly at the side of cam surface 80 and has a 40 clamp actuating cam 84 projecting inwardly toward the drum below the cam surface 80.

45 The master sheet clamping device upon the drum is adapted to be actuated by the cam 84 fixed to the arm 79, and comprises a clamping bar 45 85 (see Figs. 11 to 13) held in a slot provided in the drum surface by springs 85a at the ends of the drum and normally pressed in one direction by means of springs 86 to grip a master sheet between it and the side edge of the slot in the 50 drum. Mounted within a plate 87 on the drum is a bar 88 which is adapted to cooperate with rollers 89 and 90 rotatably mounted in the clamping bar 85. It will be noted that the bar 88 has 55 spaced slots 91 and 92 therein which are adapted, when aligned with the rollers 89 and 90, to permit the springs 86 to move the bar 88 as shown in Figs. 11 and 12 from the position shown in Fig. 12 to that shown in Fig. 11 to thus clamp the master sheet between an edge of the bar 88 and the adjacent edge of the drum as shown in Fig. 13. The bar 88 is slightly longer than the drum and is slidable longitudinally in the drum so as to have one end or the other projecting beyond the drum. 60 In Fig. 11, the bar 88 projects at the right hand end of the drum, while, in Fig. 12 in the released position of the clamping bar 85, the bar 88 projects at the left hand end of the drum.

65 A hand lever 93 is pivoted on a pin 93a which 70 is mounted on the side frame 20. Lever 93 is normally held up against a stop pin 93b on the frame 20 by a spring 102 which has one end connected to the lever 93 below the pin 93a and has its other end connected to a pin 102a on 75

the frame 20. The lower portion of lever 93 is made somewhat wider than the upper portion, and the lower end face of the lever 93 is curved on the arc of a circle the center of which 5 is the axis of pin 93a. A semicircular notch 104 is provided in the lower end face of the lever 93. The purpose of the notch 104 is to engage the pin 101a on the table 76 and to hold the table 76 in the position shown in Fig. 4.

10 When the lever 93 is pulled over from the position shown in Fig. 4 to the position shown in Figs. 9 and 10, the pin 101a on the table 76 is moved out of notch 104 in the lower end face of the lever 93 and past the lower end face of 15 the lever 93. This leaves table 76 free to swing clockwise about the rod 77. Arm 79 is pulled into the position shown in Fig. 9 by spring 82, and the projection 103 on table 76 rides up on the edge of arm 79 until the table 76 and arm 20 79 arrive to the position shown in Fig. 9. Pin 101a on table 76 bears against the side edge of lever 93 to hold it in place.

25 The cam member 84, when it is moved into the position shown in Fig. 9, is adapted to engage the bar 88 and shove it from the position shown in Fig. 11 to that shown in Fig. 12 to thus open the master sheet gripping mechanism as shown in Fig. 10 and permit a master sheet 100 to drop off the drum onto the delivery table 75.

30 Now as the drum continues to rotate, the pin 81 engages the cam surface 80 on the arm 79 and moves the arm 79 outward against the pull of the spring 82 (see Fig. 14). When the pin 81 reaches the upper end of the cam surface 80, 35 the arm 79 is pulled inward toward the drum to bring the arm into the position shown in Fig. 15. The pin 81 then engages the lower end of the hand lever 93 to prevent further rotation of the drum in a forward direction while the 40 shoulder at 94 on the arm 79 prevents reverse rotation of the drum unless the arm 79 is displaced simultaneously as hereinafter described. Thus in this position the drum is held, as shown in Fig. 15, with the master sheet clamping device open and in alignment with the master sheet 45 on the table 76.

50 The operator can now feed the master sheet into the clamping device, and, in order to close the clamping device on the master sheet, the operator rotates the drum in the reverse direction to its normal direction of movement. This brings the right hand end of the bar 88 into engagement with a cam member 85 (see Figs. 5 to 8) located at the right hand end of the drum 55 to thus push the bar 88 back into closing position to grip the master sheet.

55 As best shown in Figs. 5-8, the cam member 85 is mounted on a pivot arm 86 which is pivoted on a rod 97 carried on the frame 21 and yieldingly urged into operative position against a stop pin 97a on the frame 21 by a spring 98. So long as the bar 88 is in the master sheet clamping position, it does not engage the cam 60 85, so this cam remains out of operation until the master sheet is again released.

65 By the reverse rotation of the drum, the master sheet table 76 is caused to move simultaneously with the drum from the position shown in Fig. 15 to that shown in Fig. 16 because the pin 81 presses down upon the shoulder 94 to thus pull the arm 79 and with it the table 76 downwardly. It will be noted that the pin 77 of the table 76 is below the level of the master sheet 70 75 so that, as the clamping device is closed, the

table swings about the pivot 77 in such a fashion as to insure the master sheet being fully forced into the open jaw of the clamping device. The downward pull on the arm 79 also moves the guide pin 101a on the side of the table 76 (see 5 Fig. 18) down below the lower end of the operating lever 93, and, as soon as the pin 101a reaches this lower point, the spring 102 which is secured at one end to the side frame and at its other end to the operating lever 93, pulls the 10 lever back to move the pin 101a into the notch 104 in the lower end of the lever 93. This locks the lever 93 out of its stop position in the path of the pin 81 so that, upon forward rotation of the drum, the pin 81 can move past the lower 15 end of the lever 93. The projection 103 on table 76 moves the arm 79 outwardly as the table is drawn downwardly so as to move cams 80 and 84 out of the paths of the pin 81 and bar 88 respectively. This leaves the drum free to 20 rotate in a forward direction with the new master sheet clamped thereto and with everything in position to make copies from the new master sheet.

25 The master sheet table 76 and the associated arm 79 and operating lever 93 remain in the position shown in Figs. 1, 4, and 16, until it is desired to again replace the master sheet. At this time, the operator merely pulls the arm 93 over into the position shown in Fig. 9 to again cause 30 discharge of the old master sheet and to stop the drum with the clamping device open and in alignment with the master sheet table 76.

35 It will be evident from the foregoing description that this structure provides a simple effective 35 mechanism for replacing the master sheets in a duplicating device of this character. The simple manual operation of moving the lever 93 operates to positively open the master sheet clamping device and to stop the drum with the 40 open clamping device in alignment with the master sheet table for feeding a new master sheet, with the drum locked against advancing until the new master sheet is clamped in place and the master sheet releasing mechanism reset. 45

50 While certain embodiments of the invention have been shown and described, it is to be understood that it is capable of many modifications. Changes, therefore, in the construction and arrangement may be made without departing from the spirit and scope of the invention as disclosed in the appended claims in which it is the intention to claim all novelty inherent in the invention as broadly as possible in view of the prior art. 55

I claim:

1. In a duplicating machine, a rotatable duplicating drum, master sheet clamping means on said drum, a master sheet table, means for releasing said sheet clamping means, a manually operable control means including a member for actuating said releasing means, and means providing a positive stop for said drum, said control means operating to stop said clamping means in alignment with said table, and means operable 65 by rotation of said drum to close said clamping means and reset said control means.

2. In a duplicating machine, a rotatable duplicating drum, a clamp for securing a master sheet to said drum, means for pressing copy sheets 70 against said master sheet during rotation of said drum, means for rotating said drum, manually operable means to open the master sheet clamp and release the master sheet while the drum is 75 rotating, means to stop said drum after opening 75

of the clamp to permit feeding a new master sheet thereto, and means to thereafter close said clamp by rotating said drum.

3. In a duplicating machine, a frame, a drum 5 rotatably mounted thereon, master sheet clamping means on said drum, manually operable means to open said clamping means and stop the drum, said manually operable means including a positive latch mechanism preventing further advance of said drum, means to close said clamping means, and means to restore said manually operable means to its functionally inoperative position, said two last named means being operable by movement of said drum.

15 4. In a duplicating machine, a rotatable duplicating drum, master sheet clamping means on said drum, a master sheet table, a hand lever, a stop member on said drum, said hand lever being movable into the path of said stop member to stop said drum, and means operable upon movement of said lever into drum stopping position to release said sheet clamping means and align it with said master sheet table.

25 5. In a duplicating machine, a rotatable duplicating drum, master sheet clamping means on said drum, a master sheet table, a hand lever, a stop member on said drum, said hand lever being movable into the path of said stop member to stop said drum, and means operable upon movement of said lever into drum stopping position to release said sheet clamping means and align it with said master sheet table, said second named means having a means engaging said stop member to cause the drum and table to move together upon reverse movement of the drum.

30 6. In a duplicating machine, a rotatable duplicating drum, master sheet clamping means on said drum, a master sheet table, a hand lever, a stop member on said drum, said hand lever being movable into the path of said stop member to stop said drum, and means operable upon movement of said lever into drum stopping position to release said sheet clamping means and align it with said master sheet table, said second 35 named means being movable by said stop member upon reverse rotation of the drum, and said master sheet table being connected to said second named means and movably supported on the machine whereby it is maintained in alignment with the master sheet clamping means during the reverse movement of the drum.

35 7. In a duplicating machine, a rotatable duplicating drum, clamping means for securing a master sheet to said drum, means for pressing copy sheets against said master sheet during rotation of said drum, means for rotating said drum, manually operable means to open the master sheet clamping means and release the master sheet while the drum is rotating, means to stop 40 said drum after opening of the clamping means to permit feeding a new master sheet thereto, and means to thereafter close said clamping means by rotating said drum, said manually operable means comprising a hand lever, and said drum having a stop member for engaging said lever to stop the drum.

45 8. In a duplicating machine, a rotatable duplicating drum, clamping means for securing a master sheet to said drum, means for pressing copy sheets against said master sheet during rotation of said drum, means for rotating said drum, manually operable means to open the master sheet clamping means and release the master sheet while the drum is rotating, means to stop said 50 drum after opening of the clamping means to

permit feeding a new master sheet thereto, and means to thereafter close said clamping means by rotating said drum, said last named means comprising a sliding bar on said drum for closing said clamp, and a cam on the machine envelope with said bar. 5

9. In a duplicating machine, a rotatable duplicating drum, master sheet clamping means on said drum, a master sheet table supporting a master sheet adjacent to the surface of said drum, manually operable means adapted when actuated to provide a stop for stopping said drum with the clamping means in alignment with the adjacent edge of said table, and means operated by said manually operable means when it is actuated to cause opening of the clamping means as the drum rotates to bring the clamping means into alignment with the table. 10 15

10. In a duplicating machine, a rotatable duplicating drum, master sheet clamping means on said drum, a master sheet table having one edge adjacent the surface of said drum, a device for opening said clamping means as the drum is rotated, said device being normally held in functionally inoperative position, manually operable 20 means for moving said device into functionally operative position, and stop means operated by said manually operable means to stop said drum after the clamping device is opened, with the open clamping device aligned with the edge of 25 said table. 30

11. In a duplicating machine, a frame, a duplicating drum rotatably journaled therein, master sheet clamping means on said drum, a master sheet table adjacent to said drum, manually controlled cooperating means on said drum and said frame for opening said clamping means during rotation of the drum, and stop means on the drum and frame for stopping said drum, when the clamping means is open, with the clamping 35 means aligned with said table.

12. In a duplicating machine, a frame, a duplicating drum rotatably journaled therein, master sheet clamping means on said drum, a master sheet table adjacent to said drum, manually controlled cooperating means on said drum and said frame for opening said clamping means during rotation of the drum, and stop means on the drum and frame for stopping said drum, when the clamping means is open, with the clamping 40 45 means aligned with said table, said stop means comprising a projection on said drum and a lever on said frame movable into the path of said projection.

13. In a duplicating machine, a frame, a duplicating drum rotatably journaled therein, master sheet clamping means on said drum, a master sheet table adjacent to said drum, and movable in said frame between a functionally inoperative position with respect to the drum and a functionally operative position with one edge adjacent to the drum, and manually controlled means adapted when actuated to cause movement of said table to its functionally operative position, said drum having means cooperating with said 50 55 60 65 70 75 80 85 90 95 100 105 110 115 120 125 130 135 140 145 150 155 160 165 master sheet clamping means on said drum, a member on said drum movable with respect to said drum to open said clamping means, said member having a portion projecting from the drum, a hand lever having means to hold said table in functionally inoperative position, and means controlled by said hand lever for moving said member as the drum rotates to thereby open said clamping means and stop means on said drum cooperating with said hand lever to stop the drum after the clamping means has been opened.

15. In a duplicating machine, a frame, a duplicating drum rotatably journaled therein, master sheet clamping means on said drum, means for opening said clamping means as the drum rotates, a master sheet table, manually controlled stop means for stopping said drum with the clamping means aligned with said table, and a common actuating member for said stop means and said clamp opening means.

20. In a duplicating machine, a rotatable duplicating drum, master sheet clamping means on said drum, means to guide a master sheet to said

drum, a hand lever, means connected with said lever and said drum adapted upon movement of said lever into functionally operative position to open said clamping means and position the open clamping means in alignment with said guide 5 means.

17. In a duplicating machine, a frame, a duplicating drum rotatably mounted in said frame, a lever pivoted on said frame, master sheet clamping means on said drum, guide means on said frame for aligning the edge of a master sheet with said drum, and positioning means on the lever and drum to position the clamping means in alignment with said guide means.

18. In a duplicating machine, a frame, a duplicating drum rotatably journaled therein, master sheet clamping means on said drum, means for opening said clamping means, a master sheet guide, manually controlled means for positioning the drum with the clamping means in alignment 15 with said guide, and a lever on the frame operating said positioning means and said clamp opening means.

ALFRED MARCHEV.
